CLAIM

The ornamental design for the pot support, as shown and described.

DESCRIPTION

FIG. 1 is a top perspective view of the pot support;
FIG. 2 is a bottom perspective view of the pot support;
FIG. 3 is a front view of the pot support;
FIG. 4 is a back view of the pot support;
FIG. 5 is a side view of the pot support;
FIG. 6 is a side view of the pot support showing the side opposite that shown in FIG. 5;
FIG. 7 is a top view of the pot support; and,
FIG. 8 is a bottom view of the pot support.
The broken lines in the drawings depict portions of the pot support that form no part of the claimed design.
